(57) **CLAIM**

The ornamental design for recessed snag-resistant knobs for adjusting a welding shields pivot action, as shown and described.

DESCRIPTION

FIG. 1 is a perspective view showing the new design for a recessed snag-resistant knobs for adjusting a welding shields pivot action;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

Features depicted in dotted lines do not mark claimed subject matter in the present disclosure.
